UNITED STATES PATENT OFFICE.

HERMAN HANSEN, OF NEW YORK, N. Y., ASSIGNOR TO FRANCIS KEIL AND SON, OF NEW YORK, N. Y.

ELECTRIC SWITCH.

1,268,568.

Specification of Letters Patent. Patented June 4, 1918.

Application filed March 14, 1917. Serial No. 154,846.

To all whom it may concern:

Be it known that I, HERMAN HANSEN, a citizen of the United States of America, and a resident of New York, county of Bronx, 5 and State of New York, have invented a certain new and useful Electric Switch, of which the following is a specification, the same being a full, clear, and exact description of the invention, such as will enable 10 others skilled in the art to which it appertains to make and use the same.

This invention relates to electric circuit changing devices coming generally under the head of push button snap switches and 15 in particular to a switching mechanism of the class named by which one or more circuit terminals may be positively and quickly placed in electrical connection with certain contact members, or else held disengaged 20 therefrom, the whole being of comparatively simple construction and operating with certainty and precision. Other objects of the invention will be set forth in the following detailed description of the same.

25 To attain the desired end, the invention consists in the construction, arrangement and operation of parts hereinafter set forth.

In the accompanying drawings is illustrated one type of switching mechanism in 30 which the invention is embodied, and in which the separate parts of the improvement are designated by suitable reference numerals in each of the views.

Figure 1 represents a side elevation of the 35 working parts of the mechanism;

Fig. 2 is a similar view of the said parts in another position;

Fig. 3 is an end elevation, partly in section, of the shouldered disk and stop device;

40 Fig. 4 is a plan view of the mechanism assembled in a casing;

Fig. 5 is a front elevation of the same partly broken away to disclose the contact members; and

45 Fig. 6 is a view in section of the device illustrating the cams and means by which the same are operated by the push button.

Like numerals of reference indicate like parts in all the views.

50 Referring particularly to the drawings, 1 designates the preferably metallic frame supporting the working parts and ordinarily having depending side portions in which the axle 8 and bushings 78 and 79 are mounted, the said frame serving to support a man-

ually actuated device, as the push button 2. On the bushing 78 is rigidly mounted a plate 9 supporting by means of attachments 10 a movable three-point switching mechanism 50 comprising contact members 51, 52, 53, 60 preferably spaced ninety degrees apart.

To the said bushing is also securely affixed a duplex stop disk 20 having slots formed by oppositely disposed shoulders 21, 22, 23, 24, projecting alternately from each 65 side of the disk in the planes of the outer faces thereof, which disk also carries a stud 25. Another disk 30, having cams 31, 32, 33, 34, and a long inwardly projecting pin 42 and shorter similarly disposed pins 41, 70 43, 44, is rigidly fastened to another bushing 79 independently rotatable on the axle 8.

The opposite ends of a helical spring 14 encircling the bushings are respectively attached to the stud 25 and to the outer end of 75 the pin 42 adjacent to the disk 30, which spring normally serves to hold the two parts 25 and 42 so as to abut each other. A stop or detent bar 5 works in the depending sides of the frame 1 and is made with a slot to 80 engage and to be reciprocated by the cams of the disk 30, at the right hand thereof, and it also has a depending part adapted to move alternately in and out of one of the slots 21, 22, 23, 24 of the stop disk 20 at the 85 left hand portion of the same.

The lower part of the push button 2 is attached to a cross arm 3 which works vertically on rods 11 depending from the frame 1 and is normally held in an upward relation by springs 12. An actuating device, as a dog 4, is pivoted at 6 to the push button and held so that the lower portion of the same will project inwardly to respectively engage the pins 41, 42, 43, 44 by means of 90 a spring 7.

The whole device is preferably inclosed in a porcelain or other dielectric casing 13 having a plurality of terminals, as 71, 72, 73 respectively electrically connected with the 100 stationary contact members 61, 62, 63 which are preferably spaced ninety degrees apart.

In operation, the parts being in the position illustrated in Fig. 1, the depending projection of the stop or detent bar 5 will be 105 engaged at one side of the same with the slot 21 of the shouldered duplex stop disk 20, and the slot of the detent bar at the other end thereof will be engaged with the cam disk 30 between the cams 31 and 32. Upon 110

the depression of the push button 2, the cam disk 30 will be partially rotated as hereinbelow described, and the spring 14 attached to the adjacent lug 25 and pin 42 thereby 5 put under tension, inasmuch as the duplex stop disk 20 is held immovable by the detent stop 5, which rotation will cause the cam 31 to force the detent stop 5 to the right hand and to thereby withdraw the depending part 10 of the said detent out of the slot 21 of the duplex disk 20, thus allowing the spring 14 to turn the freed duplex disk 20 until its next rearward shouldered stop 24 is engaged with the bar 5, and the lug 25 is engaged 15 with the long pin 42 of the cam disk, thereby stopping the further movement of the latter. By this movement of the parts a quarter turn of both the duplex disk 20 and also of the cam disk 30 is made.

20 The cam disk and duplex disk now having each made a quarter of a revolution, the slot 21 of the duplex stop disk has moved to the position shown in Fig. 2 and the depending part of the detent bar 5 is engaged 25 with the slot 24 of the latter, while the slot at the right hand of the detent bar is engaged with the cam 34 of the cam disk 30.

Upon now depressing the push button again almost far enough to release the 30 duplex stop disk again, as shown in Figs. 2 and 3, the dog 4 pivoted to the said button at 6 and held in position by spring 7 will engage the pin 44 of the cam disk and thereby partially rotate the same. Upon a further depression of the button, the cam disk 35 will again make a quarter of a turn and the duplex stop disk will be released and make another quarter of a revolution; whereupon a subsequent depression of the push button 40 will engage the dog 4 and the pin 43 of the cam disk, and so on, both of the said disks advancing in the same direction a one-quarter of a revolution at each depression of the push button, the duplex disk 20 being 45 stopped alternately by the engagement first of a shoulder on one side thereof and then by a shoulder on the opposite side of the same with the depending portion of the detent bar.

50 The switch, preferably made with the three-point contact members 51, 52, 53, is shown in Fig. 5 with the said movable contact members respectively engaged with the stationary contact members 61, 62, 63 of the terminals 71, 72, 73. The terminal 71 may be that of the circuit of the main line, while the terminals 72 and 73 may be those of other circuits. When the switch is in the 55 position illustrated in Fig. 5 the contact members 51, 52, 53 are respectively electrically connected with the three terminals 71, 72, 73 through the intermediate contact members 61, 62, 63.

Upon depressing the push button 2 the 60 contact members 51 and 52 will be electrically connected with the terminals 72 and 73. A subsequent depression of the button will serve to electrically connect the contact members 51 and 53 with the terminals 73 and 71, while a further depression of the button will electrically connect the contact members 52 and 53 with the terminals 71 and 72.

The movable contact member is thus advanced in such a manner that the terminal 75 71 will be in electric connection with the terminals 72 and 73 at one one-quarter movement; and so that only the terminals 72 and 73; and so that the respective pairs of terminals 72 and 73, 71 and 73, and 71 and 72 80 will be electrically connected at the other three-quarter revolutions of the said movable contact member.

It will be observed that the cams of the cam member, upon being actuated *seriatim* 85 by the depression of the push button, advance with a step by step movement, and by the consequent throw of the detent stop bar the movable three-point contact member and duplex disk become released, the latter parts 90 moving in unison and synchronously with the termination of the said step movement, the parts being then held in a stationary relation by the detent bar. Each advance movement of the cam puts the helical spring 95 under tension which latter causes the movable contact member and duplex disk to rotate until stopped by the detent bar, rearward movement of the said movable parts being stopped by the lug of the duplex disk 100 and the long pin of the cam disk. By the use of the movable and stationary three-point contact members one of the latter may be put in electrical connection with either or both, or with neither, of the other two 105 stationary contact members at will.

I wish it to be understood that I do not desire to be limited to the exact details of construction shown and described, for obvious modifications will occur to persons 110 skilled in the art.

What I claim as my invention is:—

1. In a device of the class described, push button mechanism, a member formed with a plurality of cams actuated *seriatim* by the push button mechanism with a step by step movement, a spring controlled duplex disk formed by oppositely disposed shoulders projecting alternately from each side of the said disk, a stop moved by the cam to alternately release the said disk and afterward to hold the parts in a stationary relation, a movable contact member moved by said disk synchronously with the termination of each step movement of the cam member, and a stationary contact member engaged by the movable contact member.

2. In a device of the class described, a push button having an actuating device, a member formed with a plurality of cams and

- with an equal number of adjacent devices engaged *seriatim* by said actuating device and thereby advanced with a step by step movement, a spring controlled duplex disk 5 having slots formed by oppositely disposed shoulders projecting alternately from each side of the said disk, a stop moved by the cam member to alternately release the said disk and afterward to hold the parts in a 10 stationary relation, a movable contact member actuated by the spring controlled disk synchronously with the termination of each 15 step movement of the cam member, and a stationary contact member engaged by the movable contact member.
3. In a device of the class described, a member formed with a plurality of cams and having an engaging device, push button mechanism to advance the cam member with 20 a step by step movement, a spring controlled member having a device to engage the one first named and made with slots formed by oppositely disposed shoulders projecting from each side of the same, a movable contact member actuated by the spring controlled member, a stationary contact member, and a stop to hold the parts in a stationary relation after each movement. 25
4. In a device of the class described, a member formed with a plurality of cams and with a series of projecting pins, push button mechanism to advance the cam member with a step by step movement, a spring controlled member having oppositely disposed shoulders projecting from each side of the same, a transversely movable detent actuated by the cam member to alternately release and stop the spring controlled member, a movable contact member actuated by the 35 spring controlled member and a stationary contact member. 40
5. In a device of the class described, push button mechanism having an actuating device, a member formed with a plurality of cams and with an equal number of adjacent 45
- projections engaged *seriatim* by said actuating device with a step by step movement, a movable contact member, a spring controlled duplex disk and means to move the said contact member synchronously with the termination of the movement of each cam, a stop to hold the parts in a stationary relation after each movement, an additional stop formed by projections extending respectively from the cam and duplex members, and a stationary contact member engaged by the movable contact member. 50
6. In a device of the class described, push button mechanism having an actuating device, a member formed with a plurality of cams and with an equal number of adjacent 55 projections engaged *seriatim* by said actuating device with a step by step movement, a movable three-point contact member, a spring controlled duplex disk and means to move the said contact member synchronously with the termination of the movement of each cam, a stop to hold the parts in a stationary relation after each movement, and a stationary three point contact member engaged by the movable contact member. 60
7. In a device of the class described, a spring controlled member having slots formed by oppositely disposed shoulders projecting from each side thereof, a push button, intermediate mechanism to actuate said member, a movable contact member, a stationary contact member to engage the spring controlled member and a stop to hold the parts in a stationary relation after each 65 movement. 70

In testimony of the foregoing specification I do hereby sign the same in the city of New York, county of Bronx, and State of New York, this 31st day of January, 1917.

HERMAN HANSEN.
